EDWARD B. NEWILL, OF WILKINSBURG, PENNSYLVANIA, ASSIGNOR TO WESTINGHOUSE ELECTRIC & MANUFACTURING COMPANY, A CORPORATION OF PENNSYLVANIA

INSULATOR STRUCTURE

Application filed April 28, 1927. Serial No. 187,127.

My invention relates to insulator structures and particularly to insulator structures adapted for high-voltage service.

One object of my invention is to provide a structure of the above indicated character that shall permit an insulator, of a form heretofore suggested, to be constructed in series-related sections and that shall embody electrostatic-stress-distributing elements of such form as to reduce the overall length of the structure and the number of parts employed.

Another object of my invention is to provide an electrostatic-stress-distributing or directing unit that shall so differently affect the electrostatic field at its sides, facing oppositely along the longitudinal axis of an insulator, as to permit its use at either end, or at an intermediate portion of, the insulator, for proper cooperation with one or more similar units.

A further object of my invention is to provide a high-voltage insulator structure that shall be simple and durable in construction, economical to manufacture and effective in its operation.

In co-pending application, Serial No. 548,818, insulator, filed April 1, 1922 by H. B. Smith and assigned to the Westinghouse Electric & Manufacturing Company, is disclosed an insulator structure embodying an insulating rod and electrostatic-stress-distributing terminals of particular form and purpose.

In the device of the copending application, shields or terminals, adjacent to the ends of an insulating rod, are so shaped relative to each other as to widely distribute the electrostatic field and prevent its concentration at any position, as well as to form what may be called a "hollow field", or zone of extremely weak electrostatic stresses, through which the insulating member extends.

This construction, by preventing the concentration of the field and maintaining the surface of the insulating member free from dangerous stresses, is a material improvement in the high-voltage insulator art and, so far as I am aware provides a single insulator unit of higher voltage-resisting value

than any other single unit for similar service and of comparable amount and kind of material.

To accomplish the purposes of the above-mentioned insulator, its terminals are provided with toroidal or annular conducting surfaces that are very widely or gradually rounded, at all places thereon, and that are of considerably greater area, and differently related, than the surfaces of similarly-disposed terminals heretofore suggested.

For outdoor service, the terminals are constructed as a hood and a ring at the upper and lower ends of the insulator, respectively, and are, therefore, separate and distinct parts. There are also, holding or securing terminal portions outside the stress-distributing hood and ring, which add somewhat to the total length of the insulator.

It has been suggested to place two or more insulators, of the above-mentioned type, in series relation, as is done with insulators of the well-known cap-and-pin type and with insulators of other forms. Thus, there would be as many more hoods and rings employed as there were insulators joined in series, in addition to increased length in accordance with the number of insulators so joined.

It is my aim to permit insulator units, of the above-mentioned type, to be placed in series relation by the use of fewer parts, to thereby, conserve storage and handling expense, to provide a series-section insulator of shorter overall length than is obtained by merely connecting a plurality of the above-mentioned insulators, and to provide a single stress-distributing or directing unit which may be used intermediate the ends of the insulator or in the place of either the hood or the ring, above-mentioned.

Accordingly, in practicing my invention, I provide an electrostatic-stress-distributing unit, incorporating both a ring portion and a hood portion, and an insulating member or rod of such construction that one rod may be employed with two of such units at its ends, two or more rods may be employed with the units at the ends, or between the sections, of the compounded rod, and other combinations may be made and a shorter structure obtained.

The single figure of the accompanying drawing is a view, partially in elevation and partially in section, of an insulator structure embodying my invention.

5 The device comprises, in general, an insulating rod or member 2 embodying sections 3 and 4, a top member 6 for mounting the insulator, a bottom member or clamp 7 for supporting a conductor 8, a top electrostatic-
10 stress-distributing unit 10 and similar units 11 and 12 disposed intermediate the ends of the structure and at the bottom end, respectively.

15 The rod sections 3 and 4, which may be of any suitable construction and material, are shown as constructed as substantially solid cylindrical bars of porcelain or similar material having cylindrical end recesses in which internally-screw-threaded metal cups or 20 sleeves 14 are secured, as by cementing, for the reception of screw-threaded studs 15.

25 The top and bottom insulator-mounting and conductor-supporting members 6 and 7, respectively, are of usual types and need no particular description except that they are adapted for mounting on the top and bottom studs 15, respectively.

30 The units 10, 11 and 12 are preferably alike and each comprises a hood portion 17 having a rounded outer perimetral or water-drip portion 18, an annular portion 20 of maximum-potential gradient disposed intermediate the water-drip portion 18 and the center thereof, and an upper ring or toroidal portion 21.

35 These units may be variously constituted, so long as the outer surfaces thereof are conducting, as by constructing them of insulating material with a foil or other metal coating thereon, or by pressing or spinning them of sheet metal, such as copper or aluminum.

40 As here shown, the upper unit 10 is made of spun sheet-metal, with the parts 17 and 21 spun integrally from one sheet and an annular sheet-metal ring 23 inserted flush with the lower surface of the hood across a space at the base of the portion 21.

45 The unit 11 is constructed by spinning the parts 17 and 21 from separate sheets and suitably securing them to each other.

50 In any form, the units 10, 11 and 12 are each provided with one or more openings 25 to provide drainage for the center of the portion 21.

55 Dotted lines X indicate the zones of maximum electrostatic stress, although, by reason of the widely rounded contours of the surfaces 20 and 21, these stresses are considerably less concentrated than in insulators of the usual types.

60 At either sides of the lines X, the field becomes gradually weaker laterally therefrom, until, at positions adjacent to the surfaces of 65 the rod sections 3 and 4 and at the outer

water-drip portions 18, it becomes almost negligible.

Thus, at positions where surface current tends to build up and where water may cause a conducting path, the field is so reduced as to prevent breakdown from these causes. This feature protects the sections 3 and 4 against damage by corona and arcs and causes the ultimate flashover value to be substantially the same under wet, as under dry, conditions.

70 A separate toroidal member, similar to the portion 21 without the hood portion 17, may be used at the bottom of the structure, as may a separate hood member without the toroidal portion be employed at the top thereof but the combined unit shown is preferably of such construction as to serve for either or both and to render the carrying of separate hood and toroids unnecessary.

75 The combined unit is of particular advantage intermediate the ends of the insulator in conserving space and simplifying the construction thereof and, since it embodies longitudinally offset toroidal and hood portions of different shapes and dimensions, it constitutes a single means for differently affecting the field at opposite sides thereof facing the ends of the insulator.

80 The device is extremely easy to assemble by simple screwing operations and is, in general, an improvement in the field of service to which it relates.

85 While I have shown and described a particular form of my invention, changes may be effected therein without departing from the spirit and scope thereof, as set forth in the appended claims.

90 I claim as my invention:

95 1. An insulator comprising an elongated insulating structure, a hood thereon having an intermediate annular, arc-assuming portion and an outer annular water-drip portion, a member having a toroidal conducting surface longitudinally spaced from said hood and an element on said structure intermediate said hood and said member having a toroidal portion similar to said first toroidal portion and a hood portion similar to said first hood.

100 2. An insulator comprising an elongated insulating structure and a plurality of electrostatic-stress-distributing units disposed thereon in longitudinally-spaced relation to each other, each unit embodying a lower hood portion and an upper toroidal portion integrally united to each other.

105 3. An insulator comprising an elongated insulating structure and a plurality of end and intermediate electrostatic-stress-distributing units therefor, the top unit having a hood portion, the bottom unit having a toroidal portion and an intermediate unit having hood and toroidal portions.

110 4. An insulator comprising an elongated

insulating structure and a plurality of longitudinally-offset electrostatic-field-control units therefor, an upper unit having a downwardly-facing toroidal portion, an under unit having an upwardly-facing toroidal portion and a unit intermediate said upper and under units having upwardly and downwardly-facing toroidal portions for co-operation with units above and below it, respectively.

10 In testimony whereof, I have hereunto subscribed my name this 21st day of April, 1927.

EDWARD B. NEWILL.
